UNITED STATES PATENT OFFICE.

JOHN OVERN, JR., OF PHILADELPHIA, PENNSYLVANIA, ASSIGNOR TO WILLIAM CRAMP & SONS SHIP AND ENGINE BUILDING COMPANY, A CORPORATION OF PENNSYLVANIA.

GUIDE VANE FOR HYDRAULIC TURBINES.

Original application filed May 22, 1919, Serial No. 298,932. Divided and this application filed November 13, 1922. Serial No. 600,626.

To all whom it may concern:

Be it known that I, JOHN OVERN, Jr., a citizen of the United States, residing at Philadelphia, in the county of Philadelphia and State of Pennsylvania, have invented certain new and useful Improvements in Guide Vanes for Hydraulic Turbines, of which the following is a specification.

The principal object of my invention is to provide a new and improved axially mounted gate or guide vane for a hydraulic turbine. Another object of my invention is to provide such a gate with means to reduce the leakage past its ends to a minimum when the gate is partially or entirely closed. Still another object of my invention relates to establishing a strong mechanical connection between the gate and the shaft on which it is mounted. Another object of my invention is to enable a gate to be used having an improved shape to suit the flow of the water and one which will leave a clear passage for the water at all points of the gate surface. Another object of my invention is to enable the gates to be mounted in the most desirable position with respect to the axis of motion of the gate without the necessity of having the axis pass through the body of the gate. Still another object of my invention is to provide a convenient method of removing or replacing a gate without disturbing the gate shaft or other parts of the turbine. All these and other objects of my invention will be appreciated upon consideration of the disclosure of the specific embodiment as set forth in the following specification and claims and the accompanying drawings. It will be understood that modifications may be made within the scope of the invention. I will now proceed specifically to describe the embodiment shown in the drawings.

Fig. 1 is a vertical sectional view of a hydraulic turbine equipped with my improved gates.

Fig. 2 is a perspective view of a gate and its shaft and a fragment of one of the distributor plates with which the gate cooperates.

Fig. 3 is a top plan view of a gate involving a modified construction.

Fig. 4 is an elevation of the same and

Figs. 5 and 6 are sections on the lines 5-5 and 6-6 of Fig. 3.

Referring to the embodiment of my invention shown in the drawings as applied to a vertical shaft unit, the runner vanes 12 are adapted to be actuated by radial inflow of water from the turbine casing 14. The water passing from the spiral casing 14 goes between the fixed vanes 15 and then between the adjustable wicket gates or vanes 16. The gates 16 stand in a circular row, below them being the distributor plate or wearing ring 17 and above the distributor plate or wearing ring 21. The distributor plate 17 has suitable holes to receive the pintles 18 on the respective gates, and is also counterbored to form shallow cylindrical recesses 28 to receive the corresponding enlarged disks 26 integrally connected with the pintles 18 and rigidly fastened to the gates 16. Similarly above the gates 16 the distributor plate 21 is counterbored to form shallow cylindrical recesses 29 that receive the collars 27 integral with the operating shafts or stems 19 and rigidly fastened to the upper portion of the gates 16. The recesses in the distributor plates 21 and 17 such for example as the recesses 28 in the plate 17 are cut as close together as may be and still leave enough metal between to guard against any breaking of the division wall thereof. The faces of the disks 26 and 27 on the sides toward the vane are made fair and flush with the surfaces of the distributor plates. By referring to Fig. 2 it will be seen that in the embodiment of the invention shown, each shaft 19 is rigidly connected to its vane 16 which in turn is rigidly connected to the lower pintle 18 and collar 26.

When the turbine is operating at normal load or nearly normal load the water will flow freely between the vanes to act on the runner vanes 12 and cause rotation of the runner. To shut the turbine down the operating ring 22 of the turbine will be rotated and through the links 24 and cranks 25 the shafts 19 will also be rotated to bring the points of gates 16 against the backs of the adjustable gates so as to close the spaces between the gates.

When the gates 16 are closed or nearly closed the difference of pressure on the opposite sides will be substantially equal to the whole head on the turbine. In the absence of collars 27, 26 and depressions 29 and 28, it would be necessary in practice to provide

at least a slight clearance between the upper and lower ends of the gates 16 and the wearing rings 21 and 17 in order to insure free motion. These narrow clearance spaces 5 would permit thin sheets of water to leak past the gates above and below. It has been the common practice heretofore to construct gates without the collars such as 27 and 26 and when the gates were closed 10 there would be these thin sheets of water leaking past adjacent to the wearing rings 21 and 17. Not only has this resulted in a loss of water that it would be desirable to save for power purposes but these leakage 15 streams have eroded the runner vanes 12, and in high head turbines that have been in use for considerable time it is not uncommon to find the outer edges of the runner vanes deeply notched opposite the wearing 20 rings above and below where the vanes have been cut into by these thin leakage streams. This notching tends to start active corrosion during normal operation. The wide collars 27, 26 of my invention almost completely 25 block off these leaks.

Another advantage of my invention is realized when as is commonly the case the thickness of the vanes 16 is less than the diameter of the shaft 19. In such a case 30 in the absence of the collars 26 and 27 it has been necessary, particularly at the point where collar 27 is now introduced, either to change abruptly from the circular section of the shaft to the vane shaped section of the 35 gate, or to extend the shaft down on the face of the vane in the form of a local swelling or lug in order to increase the cross-section of the metal at this point, and to increase the strength. If the shaft is not extended in 40 this manner the point of transition from the circular shaft to the vane shaped portion of the gate represents a section of greatly reduced strength, but on the other hand if the circular section is extended, the 45 swelling or lug thus formed on the vane surface interferes with the proper flow of water along the vane, and even at best this form of gate does not have all the strength that is desirable at the junction point between the shaft and vane. It will be seen 50 that in my improvement as exemplified in Fig. 2, there is no reduction of torsional strength for cross sections at any height. Where the shaft 19 joins the collar 27, there 55 is the same cross section as anywhere along the shaft, and where the collar 27 is fastened to the vane 16 the cross section is enough to give the same or greater torsional strength as across shaft 19. Farther down, the cross section and torsional strength of the vane will 60 ordinarily be greater than of the shaft 19.

The need for torsional strength in the assembled shaft and vane becomes apparent when it is considered that sometimes stones 65 or other hard objects may get into the water

supplied to the turbine and lodge between two consecutive wicket gates during a closing motion of the gates, whereupon practically the entire governor effort communicated through the ring 22 will be thrown on 70 one or two gate shafts 19, and it is important that the connection of the shaft 19 with its gate 16 shall be strong enough to withstand the resulting torque.

The collars 26 and 27 when accompanied 75 by suitable methods of relieving the pressure on the end faces within the distributor plates can be so arranged as to balance the hydraulic thrust tending to force the gates in an axial direction. Attention is called 80 to the relief holes 30 connecting the space below the lower pintle with the draft tube.

It is frequently possible to improve the design of the guide vanes by shifting them laterally away from their center of rotation. One reason for doing this is to place them nearer to the turbine runner and thus to reduce the width of clear space between the guide vanes and runner, while at the same time permitting the shaft to be located 90 a sufficient distance away from the runner to provide the necessary space for the bearings which support it. Another consideration which makes it desirable to be able to shift the vane with respect to its center of 95 rotation is the reduction which can be secured in this way in the hydraulic load which the governor must overcome in moving the vane.

In the specific embodiment of the invention shown in the drawings the gates 16 are made detachable from the shaft 19 and the design is such that the gate can be removed without removing the shaft above or the pintle below. The shaft 19 carries the disk 100 27 and a diametral rib or feather 32 projecting across the face of the disk 27. The gate 16 has a corresponding slot 31 filled by the feather 32. A transverse pin 33 through the gate 16 and the feather 32 keeps the 105 parts in assembled relation. The joint between the gate and the pintle on the lower side is of exactly the same character. Heretofore it was common when it was desired to remove a single gate, to remove the turbine head cover because the removal of the gate required the removal of the shaft on which it was mounted. By the present invention, if a particular gate is to be removed the pins 33 will be driven out and 110 then the gate can be displaced horizontally in the direction of the slot 31 and key 32 and at any time it, or a substitute gate, can readily be replaced. At all points the cross sections may be made sufficient to give the 115 same strength as that of the cross section of the shaft 19. In this case the collar 27 not only affords a check against leakage but gives a base for the rib 32 with adequate 120 cross section for torsional strength.

This application is a division of my co-pending application Serial Number 298,982, filed May 22, 1919.

I claim:

5. 1. In a hydraulic turbine, an annular plate at the water inlet to the runner, a series of wicket gates at said inlet, rotatable shafts each carrying a respective collar, and a detachable connection between each collar and a respective gate, said annular plate having recesses to receive the respective collars.
10. 2. In a hydraulic turbine, an annular plate at the water inlet to the runner, a series of wicket gates at said inlet, rotatable shafts for the respective gates each shaft being detachably connected with its gate at a point adjacent to said plate.
15. 3. In a hydraulic turbine, an annular plate at the water inlet to the runner, a series of wicket gates at said inlet, rotatable shafts for the respective gates each shaft being detachably connected with its gate at a point adjacent to said plate and means associated with each gate to prevent leakage past its ends.
20. 4. In a hydraulic turbine, a wicket gate, a shaft therefor, a distributor plate with a hole through which the shaft passes, said plate having a recess around said shaft adjacent to said gate, a collar on the shaft in said recess, and means detachably connecting said collar and gate.
25. 5. In a hydraulic turbine, a wicket gate, a shaft therefor, a distributor plate with a hole through which the shaft passes, said plate having a recess around said shaft adjacent to said gate, a collar on the shaft in said recess, and a feather and slot connection between said collar and gate.
30. 6. In a hydraulic turbine, a wicket gate, a shaft therefor, a distributor plate with a
35. 7. A turbine having a guide vane supported between walls of a water passage, and a shaft which passes through one of said walls and serves as a pivot for said guide vane, said guide vane having provisions to render the same detachable without disturbing said shaft.
40. 8. A turbine having an adjustable throttle guide vane supported between walls of a water passage, adjusting means for said vane extending through one of said walls, said guide vane having provisions for rendering the same detachable without disturbing said means.
45. 9. A hydraulic turbine having controlling means comprising a part subject to the action of water flowing through said turbine and movable to variably guide the flow, and operating means for said part comprising connecting means between the part and its operating means permitting removal and replacement of said part without removal of said operating means.
50. 10. A turbine having a water passage formed of opposite walls and a wicket gate supported between said walls and extending from one wall to the other, said gate having the same sectional outline everywhere between said walls, adjusting means for said gate extending through one of said walls and said gate having provisions for rendering the same removable from said turbine and replaceable therein without disturbing said means and walls.

JOHN OVERN, JR.
